ABSTRACT

A reel for an anchor line is mounted on the underside of a boat deck with the line passing through a deck fitting. Metallic ribbon springs which are unwound from a takeup reel onto an output reel during the laying of the anchor cause the line to be rewound rather than accumulate on the deck during manual raising of the anchor. Line guides positioned on the reel supports prevent the line from fouling.

ANCHOR LINE REEL ASSEMBLY

The present invention relates to a novel reel assembly which is particularly adapted for use as an anchor line reel.

The primary object of this invention is to provide an anchor line reel assembly which may be positioned at the underside of a boat deck, for example, in the chain locker and which will automatically reel in and store the anchor line when the anchor is manually retrieved from the water after use. The reel assembly of the present invention is not intended to itself raise the anchor but rather is intended to retract and store the line which would otherwise be deposited upon the deck as the anchor is hauled in. The anchor reel is revolved to reel up the line by stressed metallic ribbon springs which are each unwound from a first reel when the anchor is lowered and onto a second reel to flex the springs in a direction opposite the direction of flexure of the spring on the first reel. The force stored in the springs by this rewinding is effective to rotate the reel in the line rewind direction when the weight of the anchor is taken off of a section of the line during manual hauling in of the anchor. However, this spring force is not sufficient to overcome the dead weight of the anchor when the boat is anchored.

The above and other objects, features and advantages of the invention will become apparent as this description proceeds.

In the drawings:

FIG. 1 is a partially exploded perspective view of a presently preferred embodiment of the invention.

FIG. 2 is a view partially in elevation and partially in vertical section along the line 2-2 of FIG. 3.

FIG. 3 is a vertical cross-sectional view taken on the line 3-3 of FIG. 2.

FIG. 4 is a view similar to FIG. 3 but showing the anchor line as having been unwound from the reel.

FIG. 5 is a detail view partly in perspective and partly in phantom lines showing the reels upon which the ribbon springs are wound.

FIG. 6 is an exploded detail view illustrating the connection of the anchor reel to one of its supports.

Referring now to the drawings, an anchor reel generally designated by reference numeral 10 is secured to the underside of a boat deck 12 by a pair of supports 14. The supports are connected to deck 12 by bolts 16 passing through holes drilled in the deck and nuts 18.

The anchor reel comprises a pair of circular end walls 20 and 22 which are connected to a central drum 24 by right angle clips 26 and rivets 28. The reel is rotatably disposed upon a fixed central axle 30 by nylon bushings 32 surrounding the axle and disposed in apertures in the end walls to function as bearings. Opposite ends of axle 30 pass through holes in bosses 34 at the lower ends of supports 14, and the axle is secured against rotation by cotter pins 36 which extend through holes in bosses 34 and in the axle as best seen in FIG. 6.

A pair of stainless steel ribbon springs 38 are disposed within and adjacent the opposite ends of drum 24. As shown in FIG. 3, when the anchor line 40 is fully reeled in, each spring 38 is wound on a takeup reel 41 with the exception of the front end of the spring which is fixed to an output reel 42 by a screw 44 or other comparable means. As seen in FIG. 1, one end of line 40 is secured to the anchor reel by a lanyard 43.

Referring to FIG. 5, the output reel 42 is positioned upon axle 30 to prevent relative rotation therebetween by means of a rod 46 which extends through an aperture in the axle 30 and which has its projecting ends positioned within a slot 48 cut into the face of reel 42.

Each takeup reel 41 is secured to the adjacent end wall 20 and 22 via bolts 50 and nuts 52. A rectangular plate 54 is associated with each set of takeup and output reels and functions to maintain the springs 38 in alignment and to prevent coils of the springs from becoming disassociated with the takeup and output reels. One end of plate 54 is connected to the takeup reel by bolt 50 and nut 52, and the other end of the plate is rotatably mounted on the axle 30 and prevented from moving along the axle by a cotter pin 56.

As seen in FIGS. 1 and 2 each of the supports 14 includes at its upper end a pair of inwardly facing flanges 57 which extend over the periphery of the end walls 20, 22 and are spaced closely adjacent thereto. The spacing between the underside of the flanges 57 and the periphery of the end walls is less than the thickness of line 40. In this manner, flanges 57 serve as line guides to preclude the possibility of the line 40 going over the top of the end walls rather than being retained on drum 24.

The operation of the anchor reel will now be described. Assuming that the anchor reel assembly is in the position shown in FIG. 3 in which the line 40 is fully retracted and wound on drum 24, when the anchor is dropped, the line 40 is pulled off of drum 24 and the anchor reel rotates clockwise. As takeup reels 41 rotate along with the drum 24 and its end walls relative to output reel 42, the springs 38 are unwound from takeup reels 41 and wound in the opposite direction on output reel 42.

As shown in FIG. 1, a knot 58 or other abutment is provided near the secured end of line 40 to prevent unwinding all of line 40 which might cause it to separate from the reel and which might damage the springs 38. The knot 58 abuts against a fitting 60 in the deck 12. When this position is reached, the springs 38 are in the position illustrated in FIG. 4 in which nearly all of the spring has been wound upon output reel 42. It will be appreciated that the length of line 40 and the number of turns of the springs 38 are correlated so that at least a portion of the springs will remain on the takeup reels 41 when line 40 is fully played out. Assuming that the anchor is raised by a person standing on the deck and pulling up the line in hand-over-hand fashion, the line 40, rather than accumulating in loops on the deck, is automatically wound onto drum 24 by virtue of the drum rotating counterclockwise under the influence of the springs 38 unwinding from the output reel 42 onto the takeup reel 41. The force stored in the springs 38 when wound on output reel 42 is insufficient to lift the anchor, but is sufficient to reel in the line 40 as explained above when the weight of the anchor is not acting on the line.

While the presently preferred embodiment of the invention has been shown and described with particularity, it will be appreciated that various changes and modifications may readily suggest themselves to one of ordinary skill in the art upon being apprised of the present disclosure. It is intended to encompass all such changes and modifications as fall within the scope and spirit of the appended claims.

What is claimed is:

1. An anchor reel assembly comprising a drum having a pair of end walls, said drum being rotatable about a fixed central axle, a pair of supports each having an end secured to opposite ends of said axle exteriorly of said end walls, means to secure the other ends of said supports to a boat deck, an anchor line disposed about said drum and having an end connected to an anchor, each of said supports having a reduced width portion extending generally parallel and adjacent to the outside of the respective end wall and having at said other end an enlarged width portion extending inwardly beyond the periphery of the respective end wall and spaced therefrom by a distance less than the thickness of said anchor line to constitute line guide means, and means to rewind said anchor disposed within said drum and including a pair of metallic ribbon springs each wound on a respective takeup reel rotatably supported upon a respective one of said end walls, a pair of output reels mounted upon said axle in fixed positions adjacent to said end walls, each of said output reels being connected to one end of the respective springs so the spring is wound upon said output reel as the anchor line is played out off of said drum, said springs being wound on said output reels in a direction opposite to which said springs are wound on said takeup reels, the force stored in said springs wound on said output reels being insufficient to reel in the line when the weight of the anchor is on the line but sufficient to reel in the line when the weight of the anchor is not transmitted to a portion of the line adjacent the drum, and a pair of plate means each fixably united at one end to one of said takeup reels and connected at the other end to said axle so as to enable rotation of the plate

means about said axle, said plate means aligning the respective springs and maintaining the springs associated with the respective takeup and output reels.

2. Apparatus according to claim 1, wherein said means to secure said supports to a boat deck are secured to the underside of the boat deck, the boat deck being provided with an aperture adjacent to said supports, and said anchor line extending through said aperture in the boat deck.
